UNITED STATES PATENT OFFICE

MORRIS J. HOFFMAN, OF CHICAGO, ILLINOIS

PAYROLL PRINTING MACHINE

Application filed March 22, 1930. Serial No. 437,994.

This invention relates to payroll printing machines, and its principal object is the provision of a machine by means of which certified names of the employees may be printed upon time cards, envelopes and the like, and having key lock control means for preventing tampering by unauthorized persons. In accordance with the present invention, a disk-like type carrier is provided for holding lines 5 of type for printing the names of the employees, and said type are locked in the type carrier, so that unauthorized persons cannot add other names thereto or substitute names for those contained in the type carrier. 10 Another object of the invention is to provide an arrangement whereby the type carrier may be readily removed from the machine and another one substituted in place thereof, whereby an unlimited number of 15 names may be printed with the machine.

With these and other objects and advantages in view, this invention consists in a name printing machine having removable and replaceable type carriers containing lines 20 of type (preferably of the names of employees) locked therein. It further consists in a name printing machine having a disk-like type carrier in which the lines of type are key locked therein and means for moving 25 said type carrier in a step by step manner, whereby the lines of type may be successively brought into printing position.

The invention further consists in the several novel features of construction, arrangement and combination of parts hereinafter 30 fully set forth and claimed.

The invention is clearly illustrated in the accompanying drawings in which—

Figure 1 is a plan of a name printing machine embodying a simple form of the present invention;

Fig. 2 is a vertical cross section taken on the line 2—2 of Fig. 1;

Fig. 3 is a plan with the top plates and parts thereabove removed to show the mechanism beneath said top plates, certain other parts being broken out to show parts therebelow;

Fig. 4 is a vertical cross section taken on the line 4—4 of Fig. 1;

Fig. 5 is a detail vertical cross section taken on the line 5—5 of Fig. 3;

Fig. 6 is a detail fragmental plan of the type carrier showing several lines of type therein;

Fig. 7 is a detail vertical fragmental cross section of the type carrier taken on the line 7—7 of Fig. 3; and

Fig. 8 is a fragmental side elevation of the base portion of the machine looking in the direction of the arrow 3 in Fig. 1.

Referring to said drawings which show a simple embodiment of the present invention, the reference character 10 designates the base of the machine which may be in the form of 65 a rectangular frame-like structure, upon the top of which is secured a flat top plate 11 which covers the major portion of the base. At one side of the base is an opening 12 through which access may be had to the interior of the base, and said opening is closed by a bar 13, to the upper edge of which is secured a top plate 14 that covers the opening in the top of the base which is left uncovered by the plate 11. The bar 13, together with its associated plate 14, form a 70 ribbon carrier and may be readily drawn out of the base to afford access to the interior thereof whenever it is desired to remove and replace the type carrier.

An inked printing ribbon 15 carried by spools 16 extend along the underside of the plate 14, the spools being rotatably mounted in the bar 13 and brackets 17 that extend down from the plate 14. The spools are provided with knobs or wheels 18 upon their outer ends, whereby the spools may be rotated to change the position of the ink ribbon.

Rotatably mounted on a post 19 is a table 90 20 upon which is removably supported the type carrier 21, said post 19 being secured to and extending up from a bar 22 which is secured to the base of the machine by screws 23. Conveniently, the table 20 may have a spindle 24 secured thereto which extends down through the post 19 and is rotatably mounted therein. Means are provided for rotating said table 20 in a step by step manner as will be hereinafter set forth for bring- 95 100

ing into printing position the lines of type that are locked in the type carrier.

The type carrier 21 is in the form of an annular disk-like structure having a flat bottom 25 and upstanding annular flanges 26 and 27 at the inner and outer edges of said flat bottom. A number of pins or other upstanding lugs 28 are provided upon the table 20 which enter openings in the bottom of the type carrier and hold the type carrier in position upon the table 20. The type 29 for printing the names of the employees are set up in box-like type holders or frames 30 and each line of type is locked in its frame 30 by a pin 31 which extends out through the end walls of the holder or frame 30 and through the type, as is clearly indicated in Figs. 6 and 7.

The outer flange 27 of the type carrier is provided with circumferentially arranged apertures 32 which receive the outer ends of the pins 31 and the inner flange 26 is provided with correspondingly arranged notches 33 for receiving the other ends of the pins 31. The ends of the pins which enter the notches 33 are formed with enlargements or heads 34 by means of which the pins may be handled and whereby the type are locked in place on the type carrier. The lines of type when placed in the type carrier extend in radial lines and with the type carrier are moved through a horizontal plane to bring them into printing position, as will be hereinafter explained.

The lines of type are locked in place in the type carrier by a key lock, so that no one except an authorized person may add or change the names locked in the type carrier. A simple locking means comprises a ring-like member 35 (see Fig. 7) which is placed upon the protruding end portion 34 of the locking pins 31 after the lines of type have been placed in the carrier, and is provided with a key lock 36 which is secured to a bar 37 fastened to the ring-like member 35 and extending diametrically through the opening thereof. Another bar 38 is secured at its ends to the inner flange 26 of the type carrier and also extends diametrically across the central opening of the type carrier.

The key lock 36 has a lock bolt 39 which engages with the bar 38 and locks the two bars 37 and 38 together, thereby lockingly holding the ring-like member 35 upon the protruding ends of the pins 31 and preventing any of the lines of type from being changed or others added to those already contained in the type carrier, except by an authorized person having the key to the lock.

The bars 37 and 38 conveniently form a handle by means of which the type carrier may be handled.

A slot 40 is provided in the top plate 14 under which the lines of type are successively brought into printing position to print

the names of the employees, whose names are contained on the lines of type locked in the type carrier. Above the slot 40 is a rubber or other cushioned striking bar 41 which is brought down upon the card or other paper upon which the name is to be printed, and said striking bar is carried by a handle 42 provided upon arms 42^a which are pivotally mounted upon a rod 43 secured in ears 44 formed on the base of the machine. To print a name upon a time card, envelope or other sheet, the sheet is laid upon the plate 14 and the handle 42 swung down thereby striking the striker bar 41 against the sheet and making the impression of the type thereon.

For rotating the table 20 and therewith the type carrier 21 to bring the several lines of type successively into printing position, the lower side of the table 20 is provided with teeth 45 (see Fig. 5), and a pawl 46 connected to an arm 47 of one handle arm 42^a is provided for engaging said teeth and advancing the table. A spring 48 connected to the arm 47 and pawl 46 is provided for holding the pawl in engagement with the teeth. The forward end of the pawl may be guided in the fork 49 supported by the cross bar 22. The arrangement of these parts is such that when the handle is swung down to print a name, the pawl is moved backward so as to engage its end with the next tooth, and when the handle is swung upward, the pawl is moved forward, thereby advancing the table and type carrier one step and bringing another line of type into printing position under the slot 40. For the purpose of returning the handle 42 to its upper position, a coiled spring 50 may be provided between the arm 47 and cross bar 22.

Removably secured to the bar 13 is a box or holder 51 in which is contained type 52 for printing the date upon the cards. A handle 53 may be provided upon the box 51 whereby the same may be withdrawn to change the date. The box 51 and type contained therein are arranged in alignment with the line of type in the type carrier which is in printing position.

If desired, the type 29 contained in each type holder 30 may include the employee's number, as well as his name, and numbers corresponding to the numbers on the lines of type may be placed upon the ringlike member 35 which locks the type holders in place. An opening 53 may be provided in the top plate 11 through which the attendant may observe the number appearing through the opening.

In the operation of the machine, the time card, or other article to be printed upon, is placed upon the top plate 14 with the line of type for the lowest number indicated on the locking ring 35 in printing position and the handle 42 swung down, thereby bringing the striking bar 41 forcibly against the card and

causing an impression to be made thereon from the type. When the handle is released and moved upward, the pawl 46 is moved forward, thereby advancing the table and 5 type carrier one step and bringing the next succeeding line of type into printing position. The next card is printed in the same manner as above described and the operation continued until all of the names contained in 10 the type carrier are printed.

When all of the names set in the lines of type and locked in the type carrier have been printed, the type carrier is withdrawn and removed from the machine and replaced by 15 another one containing lines of types for the names of other employees, and their names are printed upon cards. From this it will be seen that any number of type carriers may be used in connection with the machine, thereby enabling an unlimited number of names to 20 be used. When an employee is no longer connected with the concern, the person having charge of the machine unlocks the unlocking ring and removes the line of type for this person's name from the type carrier and replaces 25 and locks the locking ring.

From the above it will be seen that only the names of the employees connected with the concern are retained in the type carrier, and 30 that the person having charge of the machine is the one responsible for the names contained in the type carrier. This removes the chances for dishonesty, since if any cards were printed with spurious names, the person having charge of the key to the machine 35 would be held responsible.

More or less variation of the exact details of construction is possible without departing from the spirit of this invention. I desire, therefore, not to limit myself to the exact form of the construction shown and described, but intend, in the following claims to point out all of the invention disclosed herein.

45 I claim as new, and desire to secure by Letters Patent:

1. In a printing machine, the combination of a disk-like type carrier, radially extending lines of type held therein, and a single key 50 operated locking means for simultaneously locking a plurality of said lines of type in said type carrier.

2. In a printing machine, the combination of a disk-like type carrier, type holders and 55 lines of type secured therein, means for securing said type holders in said type carrier with the type extending radially thereof, and a key lock controlled locking ring engaging with said type securing means locking the 60 type in the type carrier.

3. In a printing machine, the combination of a flanged disk-like type carrier, type holders and lines of type therein, locking pins, 65 one for each type holder, extending there-through and through the lines of type con-

tained therein, said pins also engaging in openings in the flanges of said type carrier, and a key lock controlled locking ring locking- 70 gingly secured to said type carrier in engagement with said pins.

4. In a printing machine, the combination with a base, of a disk-like type carrier rotatably mounted therein and containing radially extending lines of type, a single, key 75 operated locking means for simultaneously locking a plurality of lines of type in said carrier, a striking bar handle carried by said base, and means operated by said handle for advancing said type carrier in a step by step manner.

5. In a printing machine, the combination with a base having a closed top and an opening in one side, a table rotatably mounted in said base, means for rotating said table in a step by step manner, and a disk-like type carrier removably secured upon said table, there being an opening in the top of the base through which type, carried by said type carrier, are capable of being exposed, and said type carrier being removable and replaceable through said opening in the base. 80

6. In a printing machine, the combination with a base, of a turntable rotatably mounted therein, a disk-like type carrier having a plurality of lines of type key locked therein by one locking element, said type carrier being removably held upon said turntable, a striker bar, a handle for actuating said striker bar, and table rotating mechanism operatively connected to said handle. 85

7. In a printing machine, the combination with a base having an opening in one side thereof, a ribbon holder and an inked ribbon carried thereby, said holder and ribbon being insertable through said opening into the base, a turntable rotatably mounted in said base, and a type carrier having lines of type key locked therein, said type carrier being insertable and removable through said opening in the base. 90

8. In a printing machine, the combination with a base, of a turntable rotatably mounted therein, said turntable being provided with a circular row of teeth, a pawl engaging with said teeth, a handle for actuating said pawl, 115 a disk-like type carrier removably held upon said turntable, lines of type removably secured in said type carrier, key lock control means for locking said lines of type in said type carrier, and a striker bar connected with said handle. 120

9. In a printing machine, the combination with a base having an opening in one side thereof, a ribbon holder and an inked ribbon carried thereby, said holder and ribbon being insertable through said opening into the base, a turntable rotatably mounted in said base, a type carrier insertable and removable through said opening in the base, type holders and type secured therein by pins which 125 130

- extend through the holders and type, and a ring-like locking member adapted to engage over said pins and having a key lock connection with said type carrier.
10. In a printing machine, a disk-like type carrier formed with a centrally located opening having upstanding annular flanges at its edges, lines of type extending radially between said flanges and having pins extending through the type and flanges, a locking ring engaging with said pins, and a key lock for locking said locking ring to said type carrier.
11. In a printing machine, the combination of a disk-like type carrier formed with a centrally located opening and upstanding marginal flanges, a bar secured to the type carrier and extending radially across said opening, lines of type extending radially between said flanges, locking pins connecting said type with said flanges, and projecting into the central opening of the carrier, a locking ring adapted to engage with said projecting ends of the pins and having a bar adapted to register with the bar of the type carrier, and a key lock for securing said bars together.
12. In a printing machine, the combination with a base having an opening at one side and in its top, of a removable bar and plate covering said openings, said plate being formed with a slot, a rotatably mounted type carrier having type therein adapted to be brought into register with said slot, and a date printing stamp carried by said bar.
13. In a printing machine, the combination with a base, of a turntable mounted therein and movable in a step by step manner, and a disk-like type carrier rotatably connected with said turntable, lines of type carried by said type carrier, said type carrier being provided with a key controlled locking means for simultaneously locking a plurality of lines of type in said type carrier, said type carrier being capable of being removed from said turntable and replaced by a type carrier of like character.
14. In a printing machine, the combination of a disk-like type carrier, radially extending name printing members held therein, and key operated locking means for simultaneously locking a plurality of said name printing members in said type carrier.

MORRIS J. HOFFMAN.
